art. A more detailed description is accordingly deemed unnecessary.

It is to be understood, however, that even though there is herein shown and described a preferred embodiment of the invention, the same is susceptible to certain changes fully comprehended by the spirit of the invention as herein described and within the scope of the appended claims.

Having described the invention, what is claimed as new is:

1. An attachment for an outside automobile door handle construction comprising a basing and attaching jacket adapted to encase a coacting portion of the door handle construction, said jacket being substantially channel-shaped in cross-section and open at its outer end and provided at said end with an endless annular flange and an endless outstanding bead, and an elastic cap having a disk portion with a self-closing key-hole therein and having a rim portion provided with an outstanding annular channel, said channel being interlocked with said annular bead.
2. The structure specified in claim 1 wherein said jacket is provided on one side with a lateral extension constituting a handle covering sheath.
3. The structure specified in claim 1 wherein said jacket is provided on one side with a lateral extension constituting a handle covering sheath,

said sheath having a flattened name-plate portion and being provided with bendable straps adapted to be clenched around the coacting handle.

4. A door handle and lock barrel shield of the class described comprising a hub encasing jacket, and an elastic barrel enclosing cap carried by said jacket and having a self-closing slit for passage of a key, said jacket being of elastic rubber and conforming in general shape and contour to the shape and contours of said hub and being provided with an annular bead, said cap having a channel-shaped annulus joined to said bead.
